UNITED STATES PATENT OFFICE.

FRANCIS J. MOORE, OF MINNEAPOLIS, MINNESOTA.

ROOF JACKET.

Application filed December 11, 1925. Serial No. 74,768.

My invention relates to improvements in roof jackets, and more particularly to the caps therefor, and to this end it consists of the novel devices and combinations of devices hereinafter described and defined in the claim.

In the accompanying drawings, which illustrate the invention, like characters indicate like parts throughout the several views.

10 Referring to the drawings:

Fig. 1 is a plan view of the improved roof jacket applied to a vent pipe;

Fig. 2 is a fragmentary view partly in side elevation and partly in central vertical section taken on the line 2—2 of Fig. 1; and

Fig. 3 is a perspective view of the clamping collar.

The numeral 4 indicates a vent pipe around which is applied the improved roof jacket 5 comprising telescopically connected sections spaced from said vent pipe to form an air space 6. Only the top portion of the upper section of the roof jacket 5 is shown, and the lower portion thereof has a flashing for securing the same to a roof with a watertight joint. The upper end of the air space 6 is closed by a cap 7, stamped from a single sheet of sheet lead, having a cylindrical body 8 that is telescoped onto the vent pipe 4. The cap 7, from the lower end of its body 8, flares outwardly and downwardly to form a base 9 that rests on an outturned flange 10 formed with the upper end of the upper section of the roof jacket 5.

35 Formed with the periphery of the base 9 is a flange 11 that primarily extends vertically downward below the flange 10, as indicated by broken lines in Fig. 2. This flange 11 is folded under the flange 10 and forms beaded interlocking engagement therewith and rigidly secures the cap 7 to the upper section of the roof jacket 5 with a tight joint. The cap 7 at the upper end of its body 8 curves upwardly and inwardly over the upper end of the vent pipe 4 to form the top 12 of said cap, and which top has an axial opening 13, the diameter of which is materially less than that of the body 8 and is also less than that of the internal diameter of the vent pipe 4.

50 To form a tight joint between the cap

body 8 and the vent pipe 4 there is applied around said body a transversely divided clamping collar 14, the ends of which have eyes 15 through which is inserted a nut-equipped draw bolt 16. The gap between the ends of the clamping collar 14 is closed by a joint strip 17 having sleeve-like ends 18 through which the end portions of the clamping collar 14 extend with freedom for end-wise movement. This joint strip 17 is channel-shaped in cross section and the draw bolt 16 lies therein.

Obviously, by tightening the draw bolt 16, the clamping collar 14 and joint strip 17 will be contracted onto the pliable body 8 of the sheet lead cap and distorted and press the same onto the vent pipe 4 to form a tight joint between the cap 7 and vent pipe 4. The clamping collar 14 rests on the base 9 and is held against upward movement therefrom by a pair of diametrically opposite circumferentially extended retaining lugs 19 pressed from the body 8. The retaining lugs 19 also hold the clamping collar 14 and parts carried thereby in assembled relation with the cap 7 when the same is carried in stock.

By making the diameter of the opening 13 less than that of the internal diameter of the vent pipe 4, water will be prevented from getting in between the top of the cap 7 and the upper end of the vent pipe 4. Warm air in the air space 6 from the interior of the building to which the roof jacket is applied will prevent the accumulation of frost in the upper end of the vent pipe 4.

By forming the cap 7 with a top that extends over the walls of the vent pipe 4, the cap is given a finished and neat appearance, and at the same time, as previously stated, prevents water from entering between the cap and vent pipe.

The above described invention has been put into extensive commercial use and has proven highly efficient for the purpose had in view.

What I claim is:

A cap of soft metal for roof jackets comprising, an upper cylindrical body portion, the upper end portion of which is turned inwardly to provide a flat annular top flange

adapted to rest on the top of a vent pipe and defining an axial opening of less diameter than said body portion, and a lower base portion which is flared outwardly and terminates in an annular depending flange of greater diameter than said body portion and adapted to be crimped under a flange on a

jacket, said body portion being formed with radially projecting lugs pressed from said body adjacent the flared base portion to retain a clamping collar of circular cross-section. 10

In testimony whereof I affix my signature.

FRANCIS J. MOORE.
